UNITED STATES PATENT OFFICE.

WILLIAM COOPER, OF CHICAGO, ILLINOIS.

STEAM-GENERATOR.

SPECIFICATION forming part of Letters Patent No. 283,756, dated August 28, 1883.

Application filed July 5, 1882. (No model.)

To all whom it may concern:

Be it known that I, WILLIAM COOPER, a citizen of the United States, residing in Chicago, county of Cook, and State of Illinois, have invented certain new and useful Improvements in Steam-Generators, of which the following is a specification.

My invention relates to steam-generators for supplying steam to tanks or other receptacles containing vegetables to be cooked, clothes to be washed, and for other analogous purposes; and the objects of my invention are to provide for the construction of steam-generators entirely of cast metal by means of novel forms of castings and water-tight joints, so that such generators may be made cheaper, more durable, and to withstand the required steam-pressure to fully adapt them to the purpose intended, and thereby lessen their tendency to explosions which frequently occur in those of the present day, constructed, as they are, partly of sheet metal; to protect the several parts of the generator and heated surfaces from the destructive influences to which they are subjected, and at the same time provide an extensive heating-surface for generating steam; to decrease the number of water-tight joints now necessary in the present construction of generators; and, finally, to provide a valve operating in the water-supply pipe and outside of the generator for convenience in repairs, said valve being operated by a float in the generator or other suitable means, and by the pressure of the water entering the generator in such a manner as to automatically regulate the supply of water to the generator. I attain these objects by the devices illustrated in the accompanying drawings, in which—

Figure 1 is a side elevation of a generator embodying my invention, with parts broken away to show a longitudinal section of the valve and its connection with the float; and Fig. 2, a vertical section through the generator, showing the construction of its shells.

Similar letters of reference indicate the same parts in the figures of the drawings.

A represents a suitable base, forming an ash-pit, and provided on its upper edge with a vertically-projecting annular flange, a, below which is a horizontal annular flange, b, below which is hinged in the usual manner a grate-bar, B, held in its operative position by

means of a button, c, convenient of access from the ash-pit door C; but while this arrangement of grate-bars is convenient, I do not claim it as a part of my invention, and it may be added that any other convenient form may be employed. Supported near the inner edge of the annular flange b is the inner shell, D, of the generator, which shell forms the fire-chamber, and is cast in one piece with a pipe, d, projecting above the fire-chamber and forming a combined flue and feed for the same, as will hereinafter be more fully described. The outer shell of the generator is cast in two parts, E F, the former and lower portion of which is cone-shaped to correspond with the fire-chamber, and the two parts being connected together by means of bolts e passing through corresponding flanges f g, upon the respective sections E F of the outer shell, a suitable packing, h, being employed to render the joint water-tight. The base of section E of the outer shell falls just within the flange a, and is provided with an annular flange, i, connected with a corresponding flange, k, on shell D, by bolts l, which serve to clamp the two shells together, and, with a suitable packing, form a water-tight joint between them, the flange a serving to prevent the shells from shifting out of place, though to this end they might be bolted in any suitable manner to the flange b supporting them.

Cast with the section F is a dome, G, flanged to receive bolts securing a head, H, having a central opening in which a safety-valve, I, operates, said head being also perforated (see Fig. 1) to receive steam-pipes K L, one of which pipes may lead to a cooking-vessel and the other to a vat containing clothes, and both pipes being provided with suitable cut-off valves, l m, respectively. The opening in the section F, through which the flue d passes, is provided with a surrounding annular flange, n, having its inner face beveled, whereby, when a ring, o, of soft metal is driven to place, it will wedge between the flange and the flue to form a tight joint. Jointed to the flue d is a section of pipe, M, in which is formed a chute, N, provided with a door, O, and serving as a feed through which fuel is supplied to the fire-chamber.

It will be observed that by the construction described the more important parts of the

generator, and especially those necessary to be of considerable strength and durability to stand the steam-pressure and the destructive influences of the heat, may be of cast metal and 5 conveniently and effectually connected together, so that every joint will be water-tight. Furthermore, by the particular conformation and arrangement of the shells the entire heating-surface of the fire-chamber is not only 10 utilized for generating steam, but is so protected by the surrounding water-jacket that it cannot be, except after a very long time, destroyed by the influences of heat; and it may also be added that when any of the ports are 15 injured by heat or otherwise they may be removed and a substitution of new ports be made without injury to the remaining portions of the generator, which frequently occurs in other constructions.

20 Shell F is perforated near its base and near the water-line to receive a bushing, 1, provided upon its inner end with a lug, 2, to which is pivoted an arm, 3, carrying upon its free end a float, 4, pivoted or otherwise secured to the arm, but preferably pivoted so that the float may assume an upright position without regard to the angle at which the arm is held, thereby increasing the effectiveness of the float, owing to its receiving a direct pressure of the boiling water over its broadest face. 25 Arm 3 is provided near its pivoted end with a lug, 5, to which is pivoted a valve-rod, 6, screw-threaded upon its outer end and carrying a correspondingly screw-threaded cone-shaped valve, 7, adjustable upon said rod and operating in an inlet-pipe, 8, enlarged at its inner end to receive the valve and removably joined to the bushing by a screw-threaded collar, 9, working on the projecting and screw-threaded end of the bushing.

30 In operation the valve is pushed forward to close the inlet-pipe when the float rises and lifts with it the arm 3, the pivoted valve-rod enabling the valve to move in a plane with the inlet-pipe and not pinch in the same as it 35 would if the valve-rod were rigid. The height at which the float must rise to effect this result and the desired depth of water in the boiler is

determined by the adjustment of the valve on its rod—as, for instance, as shown in Fig. 1 50 the float will have to rise much higher and the valve move farther forward to close the inlet-pipe, and hence the water is kept at a greater depth in the boiler than if the valve were at the extremity of the valve-rod. By having one 55 valve operating with a forward stroke against the column of water to close the boiler-pipe, the valve is actuated by the pressure of the inflowing water as well as by the float to throw it open, and consequently the movement of the 60 valve and its response to the demands of the boiler is made quick and positive.

Rising from about the center of the top of the fire-chamber is a slotted standard, 10, forming a guide for arm 3 to prevent a lateral motion of the arm by the float, and consequently 65 a binding of the arm on its pivot.

The valve above described is essential to the successful operation of my boiler, but is also adapted as a feed-water device to other boilers; 70 hence I do not broadly claim said valve in this application, but reserve the right to make such claim in another application.

Having thus described my invention, what I claim, and desire to secure by Letters Patent, 75 is—

1. In a steam-generator, the combination, with the base provided with the vertical flange *a* and horizontal flange *b*, of the inner and outer shells provided with overlapping flanges 80 *i k*, and supported upon and confined by said flanges *a b*, substantially as described.

2. The combination, with the inner shell or fire-chamber having cast therewith the flue *d*, of an outer shell joined to the inner shell forming an intermediate water-space and cast in two sections joined together, the upper section of which outer shell is provided with an annular flange inclined upon its inner edge and a ring-packing forming a joint between the 85 flue and said flange, substantially as described.

WILLIAM COOPER.
